LOW-TWIST TENSIONING OF BORON FILAMENT

BACKGROUND OF THE INVENTION

The production of high-strength and high-modulus reinforcing fibers of small diameter, such as, for example boron filaments, presents problems which are unique and generally unknown to the textile industry. There are generally three types of processes for producing high-strength high-modulus filaments. In one, a substrate characterized by relatively high ductility, such as tungsten, is converted by deposition of a coating material to a continuous fiber characterized by high rigidity, such as boron. In the second, a filament characterized by high ductility, such as organic precursor materials, is subjected to heat treatment and is also converted to a fiber characterized by high rigidity, such as graphite. In the third, a filament such as sapphire is drawn from a melt. In all cases, the filament length extending between the converted fiber takeup spool and the unconverted fiber feeding means acts as a filament with a free end in that the ductile portion is relatively free to rotate or twist due to any torque applied on the converted rigid portion; where a torque is so applied there is thus imparted a residual twist to the converted filament. Because of their strength and stiffness, it is necessary to wind such filaments on relatively large diameter spools under considerable tension in order to prevent both breakage and slippage during handling and shipping. Unfortunately, most types of equipment normally used to impart tension to filaments during winding are inadequate for use with filaments undergoing conversion from a filament characterized by ductility to a filament characterized by rigidity since they introduce twist to the filament and also normally result in excessive wear from abrasion. The former result is particularly troublesome since, once twist is introduced, it will be retained until the filament is cut and then recovery is rapid unless restrained. A typical consequence, where the filament is used as matrix reinforcement in the making of composite tapes, is to curl the product tape and render it virtually useless.

Although the desirability of producing a filament such as boron with zero or an acceptably low residual twist is recognized, the means to accomplish the same are immanifest. Of course, low or zero twist can be achieved by twist removal during unwinding but it will be recognized that this is a slow and expensive process. Again, low or zero twist fiber can be produced by eliminating all tensioning restraints, but this results in such a loose spool that filament recovery is difficult and expensive. It is thus recognized that the basic requirement to be met is to continuously provide suitable tension for winding of stiff filamentary material without simultaneously imparting torque thereto.

Most existing equipment, although suitable for providing tension, does not reliably meet the second, no-twist, requirement. Opposed rotating wheels between which the filament passes, for example, do not introduce twist when the wheels are retarded only if the wheels can be maintained in exact alignment. Unfortunately, even if initial alignment is achieved, it cannot practically be maintained since abrasive wear and other forces tend to destroy the alignment very rapidly and cause twist introduction. Capstan-type tensioners inherently produce torque which can be minimized only by using an uneconomically large wheel, with abrasion and wear undiminished as a problem. Multiple-wheeled tension devices have been operated with no twist, but are found to be difficult to thread, difficult to adjust to proper tension and susceptible to abrasion and wear.

SUMMARY OF THE INVENTION

The present invention relates in general to a means for handling filaments and more particularly to a means for imparting tension, while simultaneously preventing the introduction of a significant amount of twist thereto, to high-strength, high-modulus filaments during spool takeup while the filament is being converted from a relatively ductile state. It has been found, in the production of boron filament of approximately 4

5 mils diameter in a process such as that disclosed in copending application Ser. No. 618,511 filed Feb. 24, 1967, by Rice and owned by the present assignee, that a twist of greater than one turn per 10 feet of filament is significant enough to render the filament unacceptable for most applications.

10 The present invention contemplates the provision of means for uniformly applying transverse and directly opposed pressure to the moving converted filament upstream of the takeup spool. Abrasion-resistant planar surfaced members are precisely aligned parallel to the filament axis to apply the pressure and provide sufficient tension without creating twist.

BRIEF DESCRIPTION OF THE DRAWINGS

15 In the detailed description which follows, it will be convenient to make reference from time to time to the drawings in which:

20 FIG. 1 is a simple sketch, taken in elevation, of a typical tension device in use in a boron filament production system; and

25 FIG. 2 is an elevational view of a modification of the tension device shown in FIG. 1.

DESCRIPTION OF THE PREFERRED EMBODIMENTS

30 Referring first to FIG. 1, a supply spool 10 of tungsten filament 12 is drawn through a suitable vertical boron deposition chamber 14 such as described in the aforesaid copending application. The emerging boron-coated filament 16 is pulled onto a takeup spool 18 after passing through a tension device 20. In a typical operation, the boron filament is 4 mils in diameter, the takeup spool is from 3 to 14 inches in diameter, with approximately 8½ inches preferred and suitable winding tension is 15 to 200 grams, preferably 30 to 60 grams.

35 The tension device shown in FIG. 1 comprises a fixed plate member 22 and a movable plate member 24. Both plate members are provided with abrasion resistant mounts 26 and 28 having facing surfaces 30 which are planar in configuration. Typically these mounts 26 and 28 have been ground carbide plates, securely mounted on their respective plates 22 and 24 so that when the desired pressure is applied to the boron filament, the facing surfaces 30 will be precisely parallel. As will be appreciated, other hard, smooth, abrasion-resistant material in lieu of carbide can be used for a mount, such as the ceramics including boron, boron nitride and alumina. The 40 movable plate 24 is pivotally disposed on a pin 32 and is provided with means, such as the weight 34, to pivot it therearound to bring its mount 28 to a position of alignment with the other mount 26 while applying the desired transverse pressure to the filament pinched therebetween. It has been found that alignment, that is parallelism, between the surfaces 30 is critical, the permissible angular deviation between the two surfaces or between one of the surfaces and the filament axis being such that the tangent of the angle cannot be greater than the filament diameter divided by the length of the contact surface. Thus, for a 4-mil boron fiber and mounts having a one inch contact surface, the maximum permissible angular deviation is approximately 13 minutes. It should be noted that both the fixed and movable plates are adjustable in a direction perpendicular to the planar surfaces 30 so as to accommodate filaments of varying diameters as well as adjustable in a direction parallel to the planar surfaces 30 so as to present fresh portions of the surfaces 30 to the filament 16.

45 A modified tension device is shown in FIG. 2 with a movable plate 40 being pivotally supported by a pair of links 42 and 44 connected to four pivot pins 46, 48, 50 and 52. With the weight 54 provided as shown, there is provided continuing alignment of the facing surfaces independent of filament diameter. The fixed plate 56 is made adjustable by a pair of 50 horizontally disposed screws 58.

55 It will be appreciated by those skilled in the art that other configurations will be suggested by the present disclosure. It is recognized for example that the moving plate can be mounted on alignment rails for transverse movement with horizontal pressure being applied by suitable means such as a spring or a

pneumatic or hydraulic actuator or by weights. So long as the opposed wire-contacting surfaces are parallel to both the filament axis and each other and impart the requisite tension thereto as described hereinabove, wound fibers with less than one turn per 10 feet will be achieved. It has been found that contact lengths of one-eighth to 5 inches will perform satisfactorily although lengths of one-half to 1 inch are preferred. In order to prevent chipping of the mounts or breakage of the filament, the leading and trailing edges of the wire-contacting surfaces are rounded to a minimum radius of one sixty-fourth inch but preferably to one thirty-second to one-eighth inch.

In practice, with a system such as that shown in FIG. 1, boron filament produced at from 800 to 850 feet per hour was wound on the takeup spool with twist of less than one-tenth of a turn per 10 feet. When opposed rotating wheels were used, while inducing the same level of tension as the inventive device, they imparted up to nine turns per 10 feet of length with the average being approximately at between four and five turns per 10 feet.

It should be understood that while the present system has been described in relation to the production of filamentary boron, the concept pertains with regard to other similar high-strength, high-modulus filaments such as silicon carbide, silicon nitride, silica, sapphire or graphite.

While the invention has been described in connection with specific embodiments, numerous modifications may be made and it will be understood that the true spirit and scope of the invention is set forth in the appended claims.

What is claimed is:

1. In a method for continuously winding filament onto a takeup spool during conversion from a filament characterized by high ductility to a filament characterized by relatively high rigidity, the improvement which comprises:
tensing the filament by passing it between a pair of opposed plate members upstream of said spool, said plate mem- 35

bers having abrasion-resistant planar contact surfaces aligned parallel to both the axis of filament travel and each other whereby the wound filament will be imparted with a twist of less than one turn per 10 feet of length.

5 2. The method of claim 1 wherein said contact surfaces deviate from true parallelism with the filament axis by an angle not more than one whose tangent is the quotient obtained by dividing the diameter of the filament by the length of the contact surfaces.

10 3. The method of claim 2 wherein said filament is tensed by maintaining one of said plate members relatively fixed with its contact surface against the moving filament and urging the contact surface of the other of said plate members in a direction toward said one plate member into frictional engagement with said filament.

15 4. The method of claim 3 wherein said filament is selected from the group consisting of boron, silicon carbide, silicon nitride, silica, sapphire and graphite.

5. The method of claim 3 wherein said filament is boron and is tensed to 15-200 grams.

6. A method for winding filamentary boron during production wherein a filamentary substrate of relatively high ductility is coated with boron comprising:

winding a continuous strand of the boron filament onto a takeup spool, said spool rotating to pull said filament therearound

frictionally engaging said filament between a pair of opposed plate members upstream of said spool, said plate members having abrasion resistant planar contact surfaces aligned parallel to both the axis of filament travel and each other whereby there is imparted to the filament a tension of from 15 to 200 grams and the twist introduced is less than one turn per 10 feet of length.
